Application February 16, 1935, Serial No. 6,830

20 Claims. (Cl. 178—3)

This invention pertains to telegraph systems in which transmission is impressed on a single telegraph circuit from a plurality of transmitters, either alternately or successively or in any desired sequence.

As a result of continuous improvement in accuracy and speed of telegraphic transmitters and receivers, considerably higher efficient and practical operating speeds are attainable, which 10 makes it advisable to provide equipment whereby the output of two or more keyboard operators may be transmitted over a single communication channel to insure that the channel will be operated at its maximum efficiency.

Accordingly, the principal object of the present invention is provision of a telegraph system involving a single signalling channel and a plurality of transmitters arranged for efficient operation of the signalling channel at its maximum capacity 20 by automatically associating the transmitters with the signalling channel alternately or in a selected sequence.

A feature of the invention is the provision of a telegraph system having a single signalling circuit with a switching mechanism responsive to a local signalling condition established by an operator for automatically and alternately or in predetermined sequence connecting with the signalling circuit a plurality of transmitters operated by a control form.

The above and other objects of the present invention are achieved by providing a single signalling channel extending from a transmitting point where there is located a plurality of separate and distinct transmitting units, each including individual tape transmitters and start-stop distributors. The tape transmitters, as is common practice in telegraph operation, are controlled by a control tape carrying perforations 30 indicative of a message to be transmitted, and the transmitters according to this invention are controlled further by a switching control perforation prepared by the operator assigned to each unit for determining the moment of switching 40 one transmitter from the channel and connecting another transmitter thereto. Switching of the transmitters is effected through a changeover relay for each transmitter and through circuits interconnecting the changeover relays. The 45 changeover relays respond to an added control perforation accompanying the message perforations of a transmitter then transmitting to the channel to condition the changeover circuits for transmitting from another transmitter, which 50 circuits are completed when the previously effec-

tive transmitter has completed its cycle of operation incident the transmission of the character represented by the code perforations in the tape adjacent the added control perforation, thus insuring complete transmission of the last character of the message being transmitted from the then effective transmitter. 5

The invention also embodies mechanism for disabling any transmitting unit or units.

The invention will be more fully understood 10 from the following description, taken in connection with the accompanying drawing in which Fig. 1 illustrates diagrammatically a system involving two transmitting units to be connected alternately and automatically to a single telegraph transmission channel, and Fig. 2 illustrates 15 a section of controlling tape.

Apparatus at the transmitting station comprises two transmitting units 6 and 7 which are shown with transmitting unit 6 operatively connected to line conductor 8. Unit 6 comprises an automatic tape-controlled transmitter 11 associated with a transmitting distributor 12 of start-stop type whose operating or non-operating condition is controlled by stop cam 13 and start 20 magnet 14. There is provided in connection with the transmitter 11 a sixth contact element 16 which responds to a changeover perforation in row C, Fig. 2, or in an ultra-codal position in the controlling tape as prepared by a keyboard perforator, there being code perforations arranged in five rows to present characters of messages to be transmitted. 25

Transmitting unit 6 is associated with its companion transmitting unit 7 through a series circuit to line conductor 8 and also by symmetrical circuits which interconnect two control relays 17 and 18 and two timing contacts 19 and 20. An energizing circuit for magnet 14 extends from battery through winding of magnet 14, top contact of relay 17, timing cam follower 22, contact 20, and resistor 23 to ground. A companion circuit extends from battery through winding of magnet 24, top contact of relay 18, timing cam follower 25, contact 19, and resistor 26 to ground. 35 Control relay 17, whose winding is connected at one terminal to battery, may be controlled by any one of four circuit branches to ground, through manual key 27 to ground for removing a unit from service, taut-tape switch 28 to ground, tape-control member 16 to ground, and holding contact 29 of control relay 17 in series with middle contact of companion control relay 18 to ground. 40 Corresponding circuits may be traced for the energization of relay 18 through manual switch 27 to ground, taut-tape switch 28 to ground, tape-control member 16 to ground, and holding contact 29 of control relay 17 in series with middle contact of companion control relay 18 to ground. 45 Corresponding circuits may be traced for the energization of relay 18 through manual switch 27 to ground, taut-tape switch 28 to ground, tape-control member 16 to ground, and holding contact 29 of control relay 17 in series with middle contact of companion control relay 18 to ground. 50 Corresponding circuits may be traced for the energization of relay 18 through manual switch 27 to ground, taut-tape switch 28 to ground, tape-control member 16 to ground, and holding contact 29 of control relay 17 in series with middle contact of companion control relay 18 to ground. 55

30, taut-tape switch 31, ultra-codal contact 32 of tape transmitter 33, and through contacts of relays 17 and 18.

As has been noted, each of the two units 6 and 7 is provided with an automatic tape-controlled transmitter 11, and each such station has a keyboard perforator of any known construction for forming in a tape a series of code perforations representing the message and controlling the transmitter 11, but modified by addition of a special key for perforating an added ultra-codal record or perforation in row C, Fig. 2, to control contact elements 16 and 32.

Operation of the described transmission units 15 is as follows:

Beginning operation

The condition of awaiting beginning of transmission is with all batteries and circuits connected, with manual keys 27, 30 open, and with both taut-tape switches closed and relays 17, 18 held energized by circuits through the taut-tape switches because the perforation of tape for transmission has not been begun.

At the beginning of operation, attendants at units 6 and 7 begin operating their keyboard perforators to provide slack tape and immediately thereafter one of the taut-tape switches 28, 31 opens its contacts. Assuming that switch 28 is first to open, it will interrupt an obvious closed circuit to deenergize relay 17 which will close the relay locking chain contact circuit at its middle relay contact, thus providing a holding circuit for the winding of relay 18 to be effective upon that relay after taut-tape switch 31 has been opened. By release and restoration of its armature, relay 17 will close its top back contact, where a circuit will be completed from battery through starting magnet 14, contact of relay 17, timing cam follower 22, its contact 20 and resistor 23 to ground, and this closed circuit by energization of starting magnet 14 and attraction of its armature will release the stop cam 13 and will permit rotation of distributor 12. Signals in accordance with the operation of transmitter 11 as they appear in the perforated tape will be transmitted over line 8 through the rotation of distributor 12.

The condition of the apparatus of the structure after three-quarter revolution of shaft 42 is as shown in the drawing, with magnet 14 and relay 18 energized and with relay 17 deenergized and distributor 12 operating at unit 6.

Transferring transmission to another unit

After a period of time in accordance with operating instructions, each of the operators will perforate in the tape a changeover signal, row C, Fig. 2, by means of the special key in the perforator and will continue the work of perforating tape for messages to be transmitted. It is necessary that this changeover perforation be recorded in the tape in a longitudinal position having a determined relation to the last code of a message to be transmitted so that changeover from one unit to another unit shall occur between successive messages. Instructions for changeover record in the tape therefore provide for the changeover perforation being made in association with the last code perforations of the last message which is being perforated for transmission before changeover. When at the operating unit the changeover record or perforation is sensed by the contact member 16, a changeover circuit is closed to be traced from battery through winding of magnet 17 and contact 16 to ground, energizing

magnet 17 to remove ground from its middle contact and open the holding circuit of relay 18, thus permitting relay 18 to deenergize and causing relay 17 to be traced from battery through winding of relay 17, contact 29 of relay 17, and middle contact of relay 18, which holding circuit will become effective at the opening of contact 16. Top contact of energized relay 17 will have opened the controlling circuit of starting magnet 14, thus deenergizing that magnet to permit its armature to rest against the smooth edge of cam 13 through the remainder of the cycle of one code transmission. Later in the cycle of transmission and substantially at the end of the transmitting code cycle the contact member 16 is restored to its normal position shown, and timing cam follower 25 drops into a notch in timing cam 48, thus closing an energizing circuit for the starting magnet 24 at unit 7 to operate its armature 47 into its alternative position to release cam 45, permitting rotation of the brush arm of distributor 44 and permitting full operation of unit 7, pending closure of tape changeover contact 32.

It will be noted that the time required for transfer of line control from one transmitting unit to another transmitting unit will be very short when measured from the instant of stopping of shaft 42 to the instant of starting of shaft 43. When cam 13 engages armature 46, the notch of cam 48 is brought into registry with follower 25. Immediately thereafter contact 19 is engaged by follower 25, closing the energizing circuit of starting magnet 24. There follows the magnetic lag of energization of magnet 24 and the mechanical delay in the operation of its armature, both of which time intervals are very short. The loss of line time on line 8 due to shift of control from unit to unit will be but a fraction of a code cycle for each changeover operation.

Removing a unit from service

Should any operator desire to leave the transmission set, the operation will be as follows: Assuming for illustration the operator at unit 6, then at the end of the last message recorded in the tape a changeover signal is recorded and then blank tape and tape-feed perforations sufficient to permit the changeover signal to reach the transmitter feelers follow, after which, when distributor 12 has ceased operating, the switch 27 is closed. Transmission by distributor 44 continues until a recorded changeover signal reaches transmitter 33 and effects the operation of contact member 32 which energizes relay 18 whose holding circuit is open at middle contact of energized relay 17, and later upon return of contact member 32 to normal, permits deenergization of relay 18 for further operation of transmitter 44. After reopening switch 27, operation of transmitter 12 may be resumed.

Discontinuing transmission

At the end of the transmission from both units, switches 27 and 30 may be closed, each after its associated transmitter ceases operating, or both tapes may be allowed to run taut to close switches 28 and 31.

Although the invention has been described in connection with a specific form thereof, it will be understood that it has further applications and is not intended to be limited in scope by the embodiment shown herein for illustration.

What is claimed is:

1. In a telegraph system, a plurality of trans-

- mitters, changeover relays for conditioning said transmitters one by one to transmit effective printing code combinations of signals, a circuit, and means controlled by one of said transmitters while transmitting an effective printing code for closing said circuit to control said changeover relays to decondition the said one of said transmitters and to condition another of said transmitters for operation.
10. 2. In a telegraph system, a transmission line, a plurality of transmitters, means for conditioning individually one of said transmitters to transmit printing code combinations of signals to said line and rendering the other of said transmitters ineffective, and means operable by an operating one of said transmitters while transmitting an effective telegraphic code for controlling said means to decondition the said operating one of said transmitters and to condition another of said transmitters for operation.
15. 3. In a telegraph system, a plurality of transmitters, means for conditioning said transmitters successively to transmit effective printing code combinations of signals, further means effective by one of said transmitters while transmitting an effective printing code for controlling said means to decondition the said one of said transmitters and to condition another of said transmitters, and means effective thereafter to transmit code combinations of signals from the conditioned transmitter.
20. 4. In a telegraph system, a line, a plurality of printing code transmitters associated with said line, change-over control means, and means for establishing a local signal generated by one of said transmitters while transmitting a printing code to said line which operates said control means to change the control of said line from one to another of said transmitters.
25. 5. In a telegraph system, a line, a plurality of printing code transmitters associated with said line for transmission of printing code signals thereover, switching means responsive to a local signal generated by one of said transmitters while transmitting a printing code to said line, and means effective for changing said switching means between successive effective printing codes from one to another of said transmitters subsequently to stopping one of said transmitters and in a time period less than the transmission period of one printing code.
30. 6. In a telegraph system, a line circuit, a plurality of tape controlled code transmitting devices, means for conditioning said transmitting devices one at a time, a local circuit extending from a conditioned transmitter to said means, and means for applying an impulse to said circuit to operate said means to decondition said conditioned transmitter controlled by an ultra-codal perforation.
35. 7. In a telegraph system, a line circuit, a plurality of code transmitters for transmitting printing codes of impulses over said line circuit from one transmitter at a time, and means for transferring operation from one of said transmitters to another comprising a local circuit, and means under direct control of an ultra-codal perforation in a tape for rendering said local circuit effective to discontinue transmission to said line circuit from one of said transmitters and commence transmission to said line circuit from another of said transmitters.
40. 8. In a telegraph system, a line circuit, a plurality of code transmitters for transmitting printing codes of impulses over said line circuit from
- one transmitter at a time, means for transferring operation from one of said transmitters to another, and means under control of an ultra-codal perforation sensed concurrently with printing code perforations in a tape for controlling said means.
45. 9. In a telegraph system, a line circuit, a plurality of transmitters for transmitting printing codes of impulses over said line circuit from one transmitter at a time, means controlled by an ultra-codal perforation in a tape, and means controlled by said means concurrently with the transmission over said line circuit of a printing code of impulses for transferring the control of said line circuit from the then operating transmitter to another transmitter.
50. 10. In a telegraph system, a transmission circuit, a plurality of transmitters for the transmission of code signals over said circuit in response to signals sensed in a control form, means operated concurrently with the transmission of a code signal for preparing conditions for change-over to another transmitter in response to a further signal concurrently sensed in the control form, and means effective for thereafter completing the change-over.
55. 11. In a telegraph system, a plurality of transmitters having means for producing a uniform code-cycle transmission period, a transmission line common to said transmitters, transmitter-controlling circuits, contact means responsive to a transmitter and operating to close a transmitter-controlling circuit after a transmitter has reached its stop position, and starting means in another transmitter responsive to said transmitter-controlling circuit and operating to start said other transmitter in a time interval shorter than one code-cycle transmission period.
60. 12. In a telegraph system, a transmission circuit, a plurality of transmitters arranged to transmit code signals to said circuit selectively from a control form, means for preparing conditions local to said transmitters for effecting a changeover under control of a signal in the control form while transmitting to the circuit a code signal, and means under the control of said means for changing the connections from one transmitter to another transmitter in a time period less than the time period of transmission of a code signal.
65. 13. In a telegraph system, a transmission circuit, a plurality of transmitters including a rotary distributor and a record reader responsive to conditions in a control form, means for rendering said transmitters operatively effective with said circuit, and means responsive to a condition in said control form accompanying intelligence characters therein for stopping the rotary distributor of one transmitter and starting the rotary distributor of the other transmitter after the impulses indicative of the intelligence character have been transmitted.
70. 14. In a telegraph system, a transmission circuit, a plurality of transmitters, means responsive to a signal accompanying a group of intelligence signals and effective simultaneously therewith, and means operated from said means to control the establishment of conditions to render a transmitter ineffective with said circuit and render another transmitter operative with said circuit.
75. 15. In a telegraph system, a transmission circuit, a plurality of transmitters, means responsive to a signal accompanying a group of intelligence signals and effective simultaneously therewith,

- means operated from said means to control the establishment of conditions to render a transmitter ineffective with said circuit and render another transmitter operative with said circuit, and means operative after the intelligence signals have been transmitted to complete the established conditions.
16. In a telegraph system, a transmission line, a plurality of transmitters arranged to be effective for the transmission of intelligence telegraphically to said line, means for generating an electric impulse while transmitting code signals to said line from a transmitter, means controlled by said electric impulse to prepare for rendering the then operative transmitter ineffective and another transmitter effective, and means effective after the transmission of the code signal for completing the prepared conditions and starting transmission from the other transmitter.
17. In a telegraph system, a transmission line, a plurality of transmitters arranged to be effective for the transmission of intelligence telegraphically to said line, means for generating an electric impulse simultaneously with the transmission of a code signal of intelligence, relay means operated by said impulse to establish conditions preparatory to rendering the then operating transmitter ineffective and another transmitter effective, and means effective after the transmission of the code signal for completing the conditions and starting transmission from the other transmitter.

18. In a telegraph system, a line, a plurality of printing code transmitters common to said line, means in each transmitter for generating a local signal directly in response to a perforation in a tape while printing code signals are being transmitted to said line, and change-over control means responsive to said local signal for changing the control of said line from one to another of said transmitters.

19. In a telegraph system, a transmission circuit, a plurality of transmitters, means to control the establishment of conditions to render a transmitter ineffective with said circuit and render another transmitter operative with said circuit, additional means to cause said first means to be responsive to a signal accompanying a group of intelligence signals and effective simultaneously therewith, and means effective after the intelligence signals have been transmitted to complete the established conditions.

20. In a telegraph system, a plurality of transmitters, a transmission line common to said transmitters, switching means controlled by each transmitter when in its stopped condition, and means controlling the operation of said transmitters operated in response to the operation of said switching means for releasing its transmitter subsequent to the stopping of the other transmitter.
